FIG. 1 is a front perspective view of a package with staggered product slices showing our new design with the flaps at the ends of the wrapper being folded so as to lie in a plane parallel to the major faces of the slices;

FIG. 2 is a bottom plan view thereof on an enlarged scale;

FIG. 3 is a side elevational view thereof opposite that shown in FIG. 1;

FIG. 4 is an end elevational view thereof opposite that shown in FIG. 1;

FIG. 5 is a front perspective view of a modified form of the design of FIG. 1 wherein a plurality of side-by-side stacks of symmetrically staggered products slices, with the flaps at the ends of the wrapper being folded to lie in a plane perpendicular to the major faces of the slices comprise the package;

FIG. 6 is a bottom plan view thereof on an enlarged scale;

FIG. 7 is a side elevational view thereof opposite that shown in FIG. 5;

FIG. 8 is an end elevational view thereof opposite that shown in FIG. 5;

FIG. 9 is a front perspective view of another modified

form of the design of FIG. 1 wherein a stack of elongated rectangular product slices, with the flaps at the ends of the wrapper being folded so as to lie in a plane perpendicular to the major faces of the slices comprises the package;

FIG. 10 is a bottom plan view thereof on an enlarged scale;

FIG. 11 is a side elevational view thereof opposite that shown in FIG. 9; and

FIG. 12 is an end elevational view thereof opposite that shown in FIG. 9.

We claim:

The ornamental design for a package with staggered product slices, substantially as shown and described.
